ELECTRIC CIRCUIT BREAKER

David C. Prince, Swarthmore, Pa., assignor to
General Electric Company, a corporation of
New York

Application June 6, 1935, Serial No. 25,267

18 Claims. (CL 200—150)

My invention relates to electric circuit breakers for interrupting high tension power circuits. Circuit breakers of the impulse type for example wherein a jet of oil or other suitable arc-extinguishing liquid is projected by a piston, or an equivalent source of pressure, across the arc formed upon opening of the circuit have proved effective in quickly and positively interrupting high tension, alternating current power circuits. The amount of oil or arc-extinguishing liquid required for a single interrupting operation in this type of breaker is quite small as compared with the conventional tank type oil circuit breaker. Furthermore, the insulating and arc-extinguishing characteristics of the oil used in a circuit interruption are affected to a relatively slight extent. Accordingly, this type of breaker has distinct advantages in that the low oil content for example results in reduction of cost of maintenance, fire hazard, and size of the circuit breaker.

In applying this type of breaker to circuits operating at unusually high voltages, such as 287 kv., certain problems in design and operation are encountered, and it is an object of my invention in overcoming these problems to provide an improved, high tension, circuit breaker which shall have unusually high interrupting speed throughout the entire interrupting range.

A further object of my invention is the provision of a circuit breaker of the aforesaid type wherein normal operation results in uniform use of and inappreciable deterioration or decrease in insulating value of the oil or other arc-extinguishing liquid.

A further object of my invention is the provision of an impulse type circuit breaker which is of rugged construction and adapted to withstand severe shock, such as earthquake for example, without damage.

My invention will be more fully set forth in the following description referring to the accompanying drawings, and the features of novelty which characterize my invention will be pointed out with particularity in the claims annexed to and forming a part of this specification.

Referring to the drawings, Fig. 1 is an elevational view of the main portion of an electric circuit breaker embodying my invention; Fig. 2 is an elevational view, partly in section, of one of the interrupting units of the circuit breaker shown by Fig. 1; Fig. 3 is a plan view, partly in section, of contact structure and associated apparatus shown in Fig. 2; Figs. 4 and 5 are sectional and perspective views, respectively, of

contact and baffle structure shown by Fig. 3; and Fig. 6 is an elevational view of the breaker shown in Fig. 1 provided with electrostatic shielding means.

Referring to Fig. 1, there is illustrated a high tension, multiple-break electric circuit breaker of the impulse type comprising a pair of similar interrupting units 1 and 2 for interrupting a high tension power circuit indicated at 3. The units are connected in series in the circuit 3. Each interrupting unit is pivotally mounted at 4 on a stationary insulating support 5, the free terminal ends 3' of the interrupting units having a nonrigid connection with the insulating supports 6.

The operating means for both interrupting units includes an operating rod 7 which extends upwards from operating mechanism (not shown) through the hollow insulating support 5 and terminates in linkage coacting with the interrupting units. The insulating supports 5 and 6 together with the operating mechanism above referred to are suitably mounted on structural steel framework or other rigid foundation (not shown).

Referring more particularly to Fig. 2, the interrupting unit 2, which is generally similar in all respects to the interrupting unit 1, comprises a metallic supporting housing 8 which is carried at the pivot 4. To this housing is secured an elongated insulating casing 9 comprising a cylindrical tube of mechanically strong insulating material, such as fibre. The tube 9 is clamped at 10 to an annular flange of the casing 8 and is in communication with the interior of said casing. The opposite end of said tube is provided with a terminal cap 11 which forms with the tube 9 and casing 8 a reservoir for a suitable arc-extinguishing liquid, such as oil, for example.

In order to insulate the apparatus more effectively for high voltages and for protecting the interrupting unit from the effects of weather and climate, an outer insulating casing is provided, comprising in the present instance a pair of insulating shells 12 and 13 of ceramic material suitably united at adjacent ends by a flexible connection, such as a metallic bellows 14, for example. The insulating shell 12 is suitably connected at one end at 15 to an annular flange 16 of the casing 8, and the free or terminal end of the insulating shell 13 is suitably connected at 17 to a retaining member 18. The retaining member 18 is secured in turn by a ring-wedge device at 19 to the corresponding end of the insulating tube 9 and the end cap 11 is secured and sealed at 20 to the retaining member. Accordingly, the

strong fibre tube 9, rather than the outer ceramic casing, is subjected to the stresses incident to operation and accidental shock.

The annular space 21 between the tube 9 and shells 12 and 13 is sealed with respect to the interior of the tube 9 and is filled with insulating liquid, such as oil.

The oil space 21 is filled from an oil reservoir 21' formed by the casing 8. Accordingly, accidental breakage of one of the insulating shells would permit escape only of the oil in the space 21, and would not interfere with normal operation of the interrupting unit. Furthermore, since the oil in space 21 is sealed with respect to the oil in tube 9, except for an interconnecting vent in the casing cover 8'', a different insulating liquid of suitable characteristics may be used where desired between the fibre supporting tubes and ceramic insulators.

It shall be understood that any suitable insulating liquid may be used and that the term "oil" as used herein is intended to comprehend both insulating and arc-extinguishing liquids.

The mounting for the interrupting unit comprises at one end the pivotal support 4 to which the casing 8 is directly connected, and at the other end a roller 22 carried by a bracket 22'. The roller engages a flat bearing plate 23 on the support 6, thereby providing a nonrigid and sliding connection between the free end of the unit 2 and the insulating support 6. This arrangement not only provides for limited longitudinal or transverse movement of the interrupting unit relative to the support 6, such as due to temperature variations and uneven foundation settling, but also insures against damage due to shock, such as earthquake, for example.

The supports 5 and 6 each comprise an inner cylindrical member 24 of strong insulating material, as in the case of the tube 9, for supporting the central and terminal ends of the interrupting units. The outer insulating shell 25, which is resiliently connected at 26 with respect to the insulating cylinder 24, serves only as additional insulating and protective sheathing. The space 45 between the cylinders and shells is preferably filled with a suitable insulating liquid.

For the purpose of providing flexibility between the operating means and the interrupting units the interconnecting mechanism is housed in relatively movable interconnected casings. The operating rod 7 extending through the central insulating support 5 is connected through a link 26 to a contact operating lever 27 at 29 which extends through a wall of the casing 8, as illustrated, and is pivotally mounted at 28 within the casing. The operating rod 7 is guided within an extension casing 30 which is provided with a T-connection at 31 for enclosing the connection between the operating rod and the operating levers 27 of both interrupting units. The T-connection includes a sleeve member 32 extending through a wall of the casing 8 and having a sliding liquid-tight seal therewith at 33. Accordingly, a limited movement of the interrupting unit 2 about its pivotal support 4 is permitted without loss or throw of oil from the interrupting unit during operation thereof. This arrangement insures sufficient flexibility in the circuit breaker housing and mechanism structure for compensating comparatively severe stress and shock, such as above described. The housings 8 both vent into the T-housing 31 which is provided with suitable means, such as a vent pipe 31' for the removal of gas formed during

circuit interruption. If desired, a material for absorbing moisture, such as silica gel, may be used at the vent pipe for preventing accumulation of moisture in the breaker.

The circuit interrupting means comprises a plurality of pairs of contacts 34-35, 36-37, 38-39, and 40-41 connected in series and arranged generally along the longitudinal axis of the insulating tube 9. The contacts are mounted on and supported by an insulating partition 42 likewise extending longitudinally of the tube and arranged to form upper and lower chambers 9' and 9'' therein. For the purpose of providing a more effective seal between the partition and casing wall, sealing flaps 42' of suitable material such as leather are secured at the lateral edges of the partition.

The partition 42 is connected to a positioning or bracing member 43 through a plurality of links 44 forming with the partition a structural contact unit which can be inserted during assembly through the free or outer end of the tube 9. When the unit is properly positioned within the tube the member 43, as best shown by Figs. 2 and 4, is moved longitudinally with respect to the partition in a direction tending to straighten in toggle fashion the links 44. This movement and positioning of member 43 is suitably accomplished by adjusting nuts at 45 coaxing with the retaining member 17. Since the member 43 bears against the lower wall of the tube 9, the thrust exerted by the links 44 firmly braces the partition 42 against the opposite walls of the tube. This arrangement is clearly illustrated by Fig. 4 wherein the partition 42 is shown pressed by the members 43 and 44 against the upper wall of the tube 9 to form upper and lower chambers therein.

The relatively movable contact structure is illustrated more particularly by Figs. 3 and 5, each movable contact 35, 37, 39, and 41 being connected by means of a cross-piece or yoke 46 to a pair of rods 47 which are mounted on rollers 48 for reciprocal longitudinal movement with respect to the coaxing stationary contacts. The movable contact is provided with a guide stem as at 35' which is guided for reciprocal movement in the yoke 46. A resilient connection, such as spring 46', is provided between the yoke and contact, the yoke engaging a shoulder at 35'' on the contact stem for separating the contacts.

The movable and stationary contacts of adjacent pairs of contacts are electrically connected by flexible conductors 49, thereby connecting the respective pairs of contacts in series. Each stationary contact (Fig. 3) is rigidly mounted in an insulating member 50 depending from the partition 42. As illustrated by Fig. 5, the member 50 likewise provides bearings for the rod guiding and supporting rollers 48.

The stationary contact structure includes a conducting block 34a to which the contact 34 is secured, and a conductor stud 34b which connects the block 34a to the casing 8 at 34c (Fig. 2). The stationary contact of each unit nearest the casing 8 is therefore electrically connected thereto, the casings 8 being electrically connected in any suitable manner, such as by a flexible conductor (not shown). Also, the movable contact at the free end of each unit is electrically connected by a flexible conductor 11' to the terminal cap 11.

In circuit breakers of this type, arc interruption is effected by a jet of liquid across the arc,

the jet passage generally being transversely of the arc. The partition 42 is provided in the present instance with a pair of openings forming jet or exhaust passages 51 and 52 from the lower chamber 9'', which is filled with arc-extinguishing liquid, to the upper chamber 9', which is but partly filled as indicated by the oil level. A suitable number of exhaust passages are spaced along the arc path between the contacts as best illustrated by Figs. 3 and 5. Accordingly, when the liquid in the lower chamber is placed under pressure as hereinafter described during opening of the circuit, two jets of oil pass transversely through the arc path to exhaust into the upper chamber through the openings 51 and 52.

For the purpose of completely separating the exhausts from these openings so as to prevent restriking of the arc above the partition 42, an insulating baffle 53 is positioned between the exhaust openings of the passages so as to form separate enclosures for the comparatively conducting arc gases and other products of arcing. In the present arrangement, the baffle 53 comprises a ridge or fin-like structure extending longitudinally of the tube 9 and forming with the partition and tube, as illustrated by Fig. 4, separate arc chambers 54 and 55. The passages 51 and 52 accordingly extend in diverging directions, as illustrated, so as to exhaust at opposite sides of the baffle 53, thereby effectively preventing restriking of the arc beyond the baffle structure. It will of course be apparent that a plurality of pairs of oil passages may be provided so as to exhaust in staggered relation at opposite sides of the baffle.

The stationary and movable contacts abut in the closed circuit position, as illustrated by Fig. 3, the point of contact being nearly opposite one of the exhaust passages. In order to maintain the arc upon separation of the contacts in close proximity to the exhaust passages 51 and 52, the contacts are provided with offset portions 34' for maintaining the arc at the upper part of the contact as illustrated by Fig. 5. Accordingly, flow of arc-extinguishing liquid under pressure from the lower chamber across the arc path and through the exhaust passage is more effective to extinguish the arc than in the case where the arc root is at the lower periphery of the contact.

The source of pressure for driving the oil from the lower chamber through the arcs into the upper chamber in accordance with the circuit opening operation comprises in the present instance a piston 56 operable in an open end cylinder 57 formed in the casing 8. It shall be understood that any other suitable source of pressure may be used. The piston 56 is operatively connected through a link 58 to the operating lever 27 and is provided with valves 59, which are suitably disposed in the operating face of the piston, so as to be firmly sealed and closed by fluid pressure during the downward or working stroke of the piston and to open on the return stroke of the piston for passing oil above the piston to the lower reservoir 8' formed in casing 8.

In view of the fact that the space 9' above the partition 42 is in free communication with the space in the casing 8 above the piston, it will be clear that oil in the upper chamber after each interruption circulates back through the piston valves to the lower part of the reservoir. A continuous separating wall between the piston and partition 42 is formed by the wall portion 60 and the insulating end wall 60' which is secured to

the conductor stud 34b (Fig. 3) and forms a seal between the wall portion 60 and partition 42.

Coacting with the piston is another valve 61, comprising in the present instance a simple flap valve, pivotally mounted in the casing 8 at 5 62 and arranged to close the passage 61' between the piston and the lower chamber 9'' during the return or suction stroke of the piston. The valve 61 opens freely under fluid pressure on the working stroke of the piston and closes when the pressure in the lower or arc chamber 9'' exceeds that in the oil reservoir 8'.

By this arrangement comparatively fresh and clear oil is provided for each interrupting operation. That is, the oil instead of being sucked 15 back into the lower chamber after an arc-interrupting operation is drawn into the casing 8 where it is directed through the piston to the lower reservoir 8'. The entire quantity of oil directed across the four breaks during a single interrupt- 20 25 operation is small as compared with the quantity of liquid in the reservoir and lower chamber, as will be observed from the length of the piston stroke. Accordingly, the valves 59 and 61 insure practically complete use of the fresh oil supply before re-use of oil discharged into the upper chamber by circuit interrupting operation. Consequently, the rate of oil deterioration due to carbonization and other causes is uniform and hence comparatively slow.

Another function of the valve 61 is to prevent sucking of air or gas, the dielectric strength of which is considerably less than that of oil or other suitable insulating and arc-extinguishing liquids, into the lower chamber during the return stroke of the piston. The valve 61 in closing on the suction stroke of the piston prevents the formation of air or gas pockets adjacent the contact structure which might result were air or gas sucked from the upper chamber through the exhaust ports into the lower chamber. Furthermore, the presence of air or gas beneath the partition 29 would tend to defer the building up of pressure in the otherwise substantially incom- 35 40 45 pressible oil and so delay the blast effect. Also in this connection, the blast effect due to arc pressure in the case of large currents, such as short circuit currents, is most efficiently utilized by reason of the valve 61 which closes when the arc chamber pressure tends to reverse the piston.

The contact opening and closing mechanism is likewise associated with the operating lever 27 so as to coact with the piston 56. The pair of rods 47 on which the four movable contacts are mounted is connected by means of a yoke, or the like, at 63 to a link 64 in turn connected to one arm of a bellcrank 65. The crank 65 is pivotally mounted in the casing 8 at 66 and is provided with an arm 67 terminating in a cam actuated roller 68. Another arm of the crank 65 is connected to a compression spring 70 having a pivotal support at 71 with respect to the casing 8. As illustrated, the contacts are closed and spring 70 is slightly overcenter with respect to pivots 66 and 71 so as to bias the crank 65 in a clockwise direction, thereby holding the contacts in firm engagement.

The operating lever 27 is provided with a pair of cam plates 72 and 73 having cam surfaces 72' and 73' arranged to coact with the crank roller 70 68. The cam face 73' coacts with the roller 68 in the circuit opening operation and the cam face 72' in the closing operation. When the operating rod 7 is lowered, as viewed in Fig. 2, for effecting the interrupting operation, the consequent 75

counterclockwise movement of the lever 27 effects not only the working stroke of the piston 56 for placing the oil in the lower chamber under pressure but also counterclockwise rotation of crank 5 65 for opening the contacts. The cam face 73 is designed so that a comparatively quick contact separation is obtained at the initiation of the circuit opening movement, after which the rate of separation is decreased coincident with the oil 10 blast across the arcs. The compression spring 70 furthermore, after it has passed its over-center position, biases the contacts towards the completely open position.

The circuit closing operation is effected by raising the operating rod 7 and lever 27 so as to force, by means of cam face 72', the crank 65 in a clockwise direction to the position shown. During the circuit closing operation the spring 70 is again compressed and moved to its overset restrained position.

The operating mechanism above described, including the cam and over-center spring arrangement, forms no part of the present invention and is described and claimed in a copending application entitled "Electric circuit breakers" Serial No. 25,222, filed concurrently herewith by Carl Thumim and assigned to the same assignee as the present invention, and now Patent No. 2,071,185, issued February 16, 1937.

30 In efficiently interrupting a high tension power circuit by means of a multiple-break arrangement, it is essential that there be a fair degree of voltage distribution between the separate breaks. That is, in order to realize the advantage of a 35 plurality of breaks means should be provided for preventing concentration of the voltage at one or two breaks at circuit interruption. This has been done by connecting grading resistances across the contacts, but this arrangement has obvious disadvantages in actual practice due to burning out of the resistances, added cost, etc.

For the purpose of more evenly distributing the voltage between the terminals of the interrupting unit, I provide means for equalizing the electrostatic stresses along the contact path between the breaker terminals. In one arrangement, referring to Fig. 2, a conducting band, comprising in the present instance the metallic bellows connection 14, is disposed intermediate the terminals 50 of the units so as to encircle the path along which the breaks are disposed. The electrostatic field stresses are thereby more evenly distributed between the terminals with the result that more even voltage distribution at the individual breaks is obtained. It will be understood that a plurality of conducting bands may be used, the number and positioning thereof depending on the particular design and operating requirements of the breaker.

60 In another arrangement, referring to Fig. 6, the terminals of the breaker are provided with metallic shields 1' and 2' which in the present instance are of cone or hood like shape and designed so as to equalize or prevent high concentration of electrostatic stress along the contact path between the metallic housings 8 and the breaker terminals 3'. Shields of different configuration for accomplishing the same result may obviously be used.

70 It shall be understood that shielding means of the aforesaid type may be used in accordance with my invention either singly or in combination, and that my invention comprehends broadly the proper and more even distribution of potential at

the points of contact separation in a multiple-break high voltage circuit interrupter by means of electrostatic grading.

It should be further understood that my invention is not limited to specific details of construction and arrangement thereof herein illustrated, and that changes and modifications may occur to one skilled in the art without departing from the spirit of my invention.

What I claim as new and desire to secure by Letters Patent of the United States is:

1. An electric circuit breaker of the multiple break type comprising a ceramic casing, the longitudinal axis of which is substantially horizontally positioned, relatively movable contacts in said casing, and a pair of stationary supports adjacent the opposite ends of said casing, said casing being secured for relative movement to one of said supports and provided with a sliding connection with the other support for permitting sudden movements of the character of earthquake tremors of said supports without fracture of said ceramic casing.

2. An electric circuit breaker comprising a ceramic casing including a circuit-interrupting unit, a stationary support adjacent one end of said casing, operating mechanism at said support coacting with said interrupting unit, said casing being pivotally mounted on said support, and means substantially horizontally aligned with said stationary support for supporting in sliding relation the other end of said casing for permitting sudden movements of the character of earthquake tremors of said supports without fracture of said ceramic casing.

3. An electric circuit breaker of the multiple break type comprising a pair of casings, each casing including a substantially complete interrupting unit, the longitudinal axis of each casing being substantially horizontally arranged, a central stationary support on which each casing is pivotally mounted at one end so that the longitudinal axes of said casings are in general alignment, operating mechanism at said support coacting with both of said interrupting units, and a stationary support providing a nonrigid connection at the free end of each of said connections.

4. An electric circuit breaker of the impulse type comprising a pair of separate casings, each casing comprising separable contacts, an arc-extinguishing liquid and a piston for directing liquid between said contacts upon opening of the circuit, a central stationary support, each of said casings being pivotally mounted on said support, operating mechanism mounted with respect to said support coacting with the piston and the contacts in each of said casings notwithstanding variations in relative position of said casings and central support, and a support at the free end of each of said casings providing a nonrigid connection therewith.

5. An electric circuit breaker comprising means forming an arc chamber, relatively movable contacts separable to form an arc in said chamber, an arc-extinguishing medium, a piston for driving extinguishing medium from said chamber and through the arc upon separation of said contacts, and valve means interposed between said piston and arc chamber for precluding reversal of said piston in the event that the arc pressure in said chamber exceeds the piston pressure.

6. An electric circuit breaker comprising means forming an arc chamber having an exhaust opening, relatively movable contacts sep-

arable adjacent said opening within said chamber, a supply of arc-extinguishing liquid, a piston for driving a portion of said liquid through said exhaust opening from said chamber for extinguishing arcing upon opening of the circuit, means separate from said exhaust opening for collecting and returning said portion of liquid to said supply, and valve means interposed between said piston and arc chamber for precluding reversal of said piston in the event that the arc pressure, in said chamber exceeds the piston pressure.

7. An electric circuit breaker comprising relatively movable contacts, means forming separate chambers, said contacts being separable in one of said chambers, said chambers being interconnected by an opening arranged substantially opposite the point of separation of said contacts, an arc-extinguishing liquid substantially filling the contact chamber, a source of pressure for effecting flow of a comparatively small portion of said liquid through said opening and between said contacts upon a single separation thereof, and valve means for readmitting said liquid from said last-named chamber to said contact chamber and for progressively using, in accordance with successive circuit opening operations, substantially the complete unused liquid supply in said contact chamber.

8. An electric circuit breaker comprising relatively movable contacts, a partition forming separate chambers, said contacts being separable in one of said chambers, said partition having an opening interconnecting said chambers and arranged substantially opposite the point of separation of said contacts, a supply of arc-extinguishing liquid substantially filling the chamber in which said contacts are disposed, a piston for expelling a quantity of liquid from said supply chamber through said opening into the other chamber and between said contacts upon separation thereof, and valve means adapted to open in accordance with a return stroke of said piston for readmitting said quantity of liquid to said supply chamber at a point remote with respect to said partition opening.

9. An electric circuit breaker of the impulse type comprising relatively movable contacts, a partition forming two chambers in one of which said contacts are disposed, said contact chamber likewise containing an arc-extinguishing liquid, said partition having an opening interconnecting said chambers substantially opposite the point of separation of said contacts, a piston for expelling from said contact chamber a quantity of said liquid through said opening in accordance with a circuit opening operation, and a valve controlling communication between said contact chamber and said piston, said valve arranged to close during the return stroke of said piston.

10. An electric circuit breaker of the impulse type comprising relatively movable contacts, a partition forming two chambers in one of which said contacts are disposed, said contact chamber likewise containing a supply of arc-extinguishing liquid, said partition having an opening interconnecting said chambers and disposed substantially opposite the point of separation of said contacts, a piston in communication with said liquid for expelling a quantity of liquid through said opening into the other chamber in accordance with separation of said contacts, valve means associated with said piston for re-admitting said quantity of liquid to said supply chamber after a circuit opening operation, and in

accordance with the return stroke of said piston, and a valve controlling communication between said supply chamber and said piston arranged to close so as to prevent drawing of air into said supply chamber during the return stroke of said piston. 5

11. An electric circuit interrupter comprising means forming an arc upon opening of the circuit, insulating baffle structure having a plurality of passages, the entrances of said passages being spaced along the path of said arc and the exhausts of said passages being similarly spaced along said path and extending in diverging directions at opposite sides of said baffle structure, and means for directing an arc-extinguishing liquid across said arc and through said passages. 10 15

12. An electric circuit breaker comprising relatively movable contacts, a casing forming a chamber in which said contacts are disposed, an arc-extinguishing liquid in said chamber, means forming a plurality of passages leading from said chamber, the entrances of said passages disposed adjacent and in substantial alinement with the arc path formed upon separation of said contacts, a source of pressure for directing liquid from said chamber across said arc path to exhaust through said passages, and a baffle extending longitudinally of said arc path between said passages so as to separate the exhausts therefrom. 20 25 30

13. A high tension multiple-break circuit breaker comprising an elongated casing, a plurality of pairs of contacts connected in series spaced along the longitudinal axis of said casing, said casing having a partition forming two chambers in one of which said contacts are disposed, an arc-extinguishing liquid in said contact chamber, said partition having a plurality of exhaust openings adjacent each pair of contacts and spaced longitudinally of the arc path formed upon separation of said contacts, a source of pressure for directing liquid from said contact chamber through each arc path and associated exhaust openings into the other chamber upon opening of the circuit, and a baffle in said other chamber extending longitudinally of said casing and forming with said partition casing separate enclosures, said exhaust openings arranged in staggered relation to vent at opposite sides of said baffle. 35 40 45 50

14. An electric circuit breaker comprising relatively movable contacts, means forming a chamber in which said contacts operate, an arc-extinguishing liquid in said chamber, said chamber being provided with a pair of exhaust passages, 55 the entrances of said passages being disposed adjacent and in general alinement with the arc path formed upon separation of said contacts, a source of pressure for directing liquid from said chamber across the arc path into said passages, said passages exhausting in diverging directions, and a baffle the longitudinal axis of which is generally parallel to said arc path disposed between the exhaust openings of said passages for completely separating the exhausts therefrom. 60 65

15. An electric circuit breaker comprising relatively movable contacts, means forming a chamber in which said contacts are disposed, an arc-extinguishing liquid in said chamber, said chamber having an exhaust opening substantially opposite the arc path formed upon separation of said contacts, said contacts having coating raised portions at points nearest said exhaust opening for retaining the arc near said opening, and a source of pressure for directing liquid from 70 75

said chamber across said arc and through said exhaust opening in accordance with separation of said contacts.

16. An electric circuit breaker comprising an elongated casing, a structural unit including relatively movable contact structure arranged to be removably mounted in said casing, relatively movable means connected to said unit and adapted to engage a wall of said casing, said means being movable to a nonobstructing position when said unit is placed in said casing, and coacting adjusting means for bracing said unit in position with respect to said casing wall.
17. A high tension multiple-break electric circuit breaker comprising a cylindrical insulating tube, a removable partition extending longitudinally of said tube dividing the same into chambers, relatively movable contacts mounted on said partition, a member extending longitudinally of said casing and connected to said partition through a plurality of links, said partition, contact structure, and member forming a unit adapted to be placed in position through one end of

said tube, and means for adjusting said member relative to said partition so as to force by means of said links said member and said partition into engagement with opposite walls of said tube.

18. An electric circuit breaker comprising means forming an arc chamber having an exhaust opening, relatively movable contacts separable within said chamber substantially opposite said opening, a supply of arc-extinguishing liquid, part of which is in said chamber, means for creating pressure in said chamber for expelling some of said liquid from said chamber through said exhaust opening upon separation of said contacts for extinguishing arcing, means separate from said arc chamber for returning said exhaust liquid to said supply so that said exhaust liquid is used again only after substantially complete use of the unused supply, and valve means for controlling said liquid return in accordance with operation of said pressure-creating means.

DAVID C. PRINCE.

CERTIFICATE OF CORRECTION.

Patent No. 2,162,588.

June 13, 1939.

DAVID C. PRINCE.

It is hereby certified that error appears in the printed specification of the above numbered patent requiring correction as follows: Page 2, second column, line 38, after the word and period "therein." insert the following sentence -

The contact unit is readily withdrawn through the outer end of tube 9 by moving the member 43 in a horizontal direction (to the right as viewed in Fig. 2) so that the toggle at 44 collapses and the partition 42 drops away from its braced position.; and that the said Letters Patent should be read with this correction therein that the same may conform to the record of the case in the Patent Office.

Signed and sealed this 8th day of August, A. D. 1939.

Leslie Frazer,
Acting Commissioner of Patents.
